ABSTRACT

An interest-paying savings bank having a coin container provided with a savings coin receiver and an interest coin magazine with gate means adapted to release coins from the magazine into the container and actuating means responsive to the placement of a savings coin in the receiver for actuating the gate means and releasing an interest coin from the magazine into the container. The container having transparent window means so that the operator may watch an interest coin being deposited automatically in response to the placement of a savings coin in the receiver of the container.

FIG. 3

INTEREST-PAYING SAVINGS BANK

BACKGROUND OF THE INVENTION

It has been desirable to teach children and other persons to save money and to recognize the possibility of receiving interest on money placed in the bank. It has been desirable graphically to help children recognize the possibility that money saved may grow relative to the interest paid thereon by conventional savings account practices, normally offered by banking institutions. Prior art savings banks for children have heretofore been provided with simple means for receiving coins which are to be saved. However such banks have not contained any means for graphically portraying the interest paid on a savings account such as those managed by banking institutions.

SUMMARY OF THE INVENTION

The present invention relates to an interest-paying savings bank adapted graphically to illustrate the payment of interest in response to the placement of a savings coin placed in the savings bank. The invention applies a novel interest coin magazine adapted to contain several coins such as pennies or the like and this magazine is in the container body of the bank and provided with an opening at the outside thereof for receiving a plurality of interest coins such as pennies which a father or parent may place in the magazine and this magazine is provided with a gate operable in response to savings coins placed in a receiver of the main container of the savings bank so that an interest coin such as a penny may automatically be released from the magazine each time a savings coin is placed in the main container receiver.

Additionally the container is provided with windows which may provide a visual view of the interest coins being automatically released from the magazine when the savings coins are inserted in the receiver of the bank container.

The invention comprises simple lever means for operating the gate and it is provided with a pair of stops concurrently operable and spaced apart so as to release one coin from the magazine while holding back the remaining coins in order that each movement operation of the gate means releases one coin at a time in response to the placement of a savings coin in the receiver of the container. The leverage means of the invention between the magazine release gate and the savings coin receiver is such that the savings coin merely lands on one end of the lever and tilts it for actuating the magazine gate means which is connected to the opposite end of the lever. The mechanism of the gate means and the magazine outlet communicating with the interior of the bank container as well as the areas in which the savings coins and interest coins drop into the container are readily visible through transparent window means in the side of the container so that children or other persons may visually witness the deposit of interest coins in the container in response to the deposit of respective savings coins in the receiver of the container.

Accordingly, it is an object of the present invention to provide an interest-paying savings bank which graphically illustrates to children or other persons interest paid on savings deposited in the bank.

Another object of the invention is to provide a novel means for depositing interest coins in response to the deposit of savings coins and to provide visual inspection means so that the automatic deposit of the interest coins may be observed in response to the deposit of savings coins in the receiver of the bank.

Another object of the invention is to provide a very simple and reliable means for operating a mechanism adapted to deposit interest coins in the bank in response to the deposit of savings coins therein.

Further objects and advantages of the invention may be apparent from the following specifications, appended claims and accompanying drawings.

BRIEF DESCRIPTION OF THE DRAWINGS

FIG. 1 of the drawings is a perspective view of an interest-paying savings bank in accordance with the present invention and showing portions of the container thereof broken away so as to amplify the illustration and to expose details of the interest coin magazine and the savings coin receiver mechanism;

FIG. 2 is an enlarged fragmentary sectional view taken from the line 22 of FIG. 1;

FIG. 3 is an enlarged vertical sectional view of the interest coin magazine taken from the line 33 of FIG. 1; and

FIG. 4 is an enlarged fragmentary exploded view of the interest coin magazine and coin release gate mechanism therefor.

DESCRIPTION OF THE PREFERRED EMBODIMENTS

As shown in FIG. 1 of the drawings, a savings bank container 10 is adapted to act as a coin enclosure and is of a configuration which simulates a house with a chimney and windows. The container is provided with a bottom 12, sides and ends 14 and 16, and a roof 18 through which a simulated chimney 20 extends. The chimney simulating structure is actually a savings coin receiver having a coin receiving slot 22 adapted to receive savings coins such as twenty-five cent pieces or the like. This slot 22 is substantially vertically disposed so that coins inserted in the slot 22 may gravitate into the interior 24 of the savings bank container 10.

As shown in FIG. 2 of the drawings, the slot 22 communicates with a substantially vertical coin guide 26 which is hollow and adapted to guide a coin shown by broken lines 28, downwardly into engagement with a gate actuating lever 30 as will be hereinafter described.

The guide 26 is provided with a lateral opening 32 to allow a coin 28 to follow a path 34 around an end 36 of the lever 30 when it is pivoted to a broken line position 38 by weight of the savings coin 28. The lever 30 is pivoted on a pin 40 carried by the coin receiver housing 42 which forms part of the chimney simulating structure 20 and supports the coin guide 26.

The lever 30 is provided with an opening 44 in which a link 46 is pivoted and the opposite end 48 of the link 46 is pivotally connected to a gate member 50 which is movable operable in relation to a normally lower end 52 of an interest coin magazine 54 which is shown best in FIGS. 1 and 3 of the drawings, but which is also shown in FIGS. 2 and 4 of the drawings.

The gate member 50 is provided with a coin stop portion 56 which reciprocates in an opening 58 in an upper portion of the interest coin magazine 54. This magazine 54 as shown in FIG. 2 of the drawings is generally chan-

nel shaped in cross-section and is secured to a side wall 60 of the container 10 opposite to the side wall 14 shown in FIG. 1 of the drawings.

The gate member 50 is also provided with a coin stop portion 62 stepped relative to the coin stop portion 56 and reciprocally movable in an opening 64 in a lower portion of the channel shaped interest coin magazine 54.

The stop portion 56 shown in FIG. 4 is directed downwardly while the stop portion 62 is directed upwardly and both stops are fixed together by means of an interconnecting portion 66 of the gate member 50 so that these stops 56 and 62 operate in unison as indicated best by broken lines in FIG. 2 of the drawings wherein the stop portions 56 may be moved upwardly to clear an upper portion 67 of an interest coin 68 while the stop portion 62 moves upward to a broken line position 70 between a lower most interest coin 68 and the remaining coin 68 in the declining coin magazine 54. Thus the upper portion 66 of the lower most coin 68 clears the stop 56 when in its upper most broken line position 56 as shown in FIG. 3 of the drawings, thus allowing the lower most coin in the magazine to escape through a delivery opening 72 at the lower end of the magazine 54 while the stop 62 in its broken line position 70 holds the remaining coins back. Thus one coin is delivered from the magazine 54 each time a savings coin 28 tilts the lever 30 to its broken line position 38 and thereby moves the link 46 together with the gate member 54 to move the stop portion 56 and 62 to the broken line position shown in FIG. 3 for releasing one coin from the lower delivery end 72 of the interest coin magazine 54.

The interest coin magazine 54 is provided with an open end portion 76 communicating with a slot 79 in the end 16 of the container 10 to receive interest coins and a resilient plate spring 78 may be deflected by the coin 68 as they are forced into the magazine 54. However this plate spring 78 tends to be in the solid line position shown to prevent coins from falling from the magazine 54 and outwardly through the slot 79 when the savings bank is tilted toward the side 16. Thus the member 78 in the broken line position 80 as shown in FIG. 3 of the drawings allows interest coins to be inserted into the magazine 54 by forcing them against the member 78 and deflecting it to the broken line position 88 following which it resiliently returns to the solid line position and prevents the coins from being lost from the magazine during tilting of the bank.

It will be understood that the invention encourages children or other persons to place savings coins in the receiver slot 22 and to visually experience the payment of interest coins into the bank in response thereto. Transparent windows 90 and 92 afford a view of the savings coins falling into the interior 24 of the container 10 from the receiver slot 22 and from the delivery end 72 of the magazine 54 respectively. Accordingly it will be appreciated that children or other persons are graphically taught the interest bearing principle relative to savings placed in the bank. A father or other parent may supply pennies or other interest coins to the magazine 54 as herein before described so that these coins will automatically be deposited in response to the placement of savings coin 28 in the receiver slot 22 and in each instance the savings coin will operate or move the gate 50 relative to the magazine 54 and cause

the gate 52 to allow an interest coin to be deposited in the interior 24 of the container 10.

It will be appreciated that the magazine 54 is inclined as shown in FIG. 3 so that gravity is responsible for depositing the coins from the magazine 54 and into the interior 24 of the container when the gate 50 is operated.

Additionally, it will be appreciated by those skilled in the art that the leverage provided by the lever 30 corresponding to weight of the savings coins is coordinated with the inclination of the magazine 54 and the relative weight of the gate 50 as well as its frictional engagement with the coin 68 in order to provide for reliable actuation of the gate 50 as hereinbefore described.

The construction is shown in FIGS. 1 to 4 of the drawings has operated very reliably in a working model and the simplicity of the mechanism affords trouble-free, long life operating characteristics.

It will be obvious to those skilled in the art that various modifications of the invention may be made without departing from the spirit of the invention.

We claim:

1. A toy savings bank adapted to encourage children to save coins by immediately rewarding them with an additional coin for each deposited coin, said bank comprising:

- a. a coin input guide, said guide having one end terminating within said bank;
- b. a pivoted lever mounted within said bank, one arm of said lever extending into proximity with said end of said guide, said lever being pivotally actuated by any coin passing through said guide;
- c. a magazine disposed within said bank for temporarily storing a plurality of additional coins, said magazine including an input opening for loading said magazine and a delivery opening for emptying said magazine into said bank; and
- d. a gate member responsive to pivotal movement of said lever, said gate member selectively releasing one of the additional coins from said magazine; whereby, a coin deposited through said guide causes an additional coin from said magazine to be deposited within said bank and simulate the payment of interest.

2. The bank as set forth in claim 1 wherein said magazine comprises a channel shaped member for storing the additional coins edge to edge in an upright position.

3. The bank as set forth in claim 2 wherein said magazine is inclined to urge the additional coins to roll toward said delivery opening.

4. The bank as set forth in claim 3 wherein said magazine is disposed within said bank and said input opening comprises a slot through a wall of said bank.

5. The bank as set forth in claim 3 wherein said magazine includes a spring for inhibiting removal from said magazine of the additional coins through said input opening.

6. The bank as set forth in claim 3 wherein said gate member pivotally depends from another arm of said lever and urges said one arm of said lever toward said guide.

7. The bank as set forth in claim 6 wherein said gate member is reciprocally movable from a first position to a second position in the vertical axis in response to pivotal movement of said lever.

8. The bank as set forth in claim 7 wherein said gate member includes a downwardly extending portion for

inhibiting the passage of an additional coin adjacent said delivery opening when said gate member is in said first position and an upwardly extending portion for inhibiting movement of the penultimate additional coin adjacent said delivery opening when said gate member is in said second position; whereby, only one of the additional coins is released during each cycle of reciprocal movement of said lever.

9. The bank as set forth in claim 8 wherein said magazine includes an aperture for receiving said down-

wardly extending portion and a further aperture for receiving said upwardly extending portion; whereby, said upwardly and downwardly extending portions are insertable within said channel shaped member.

10. The bank as set forth in claim 1 wherein one wall of said bank includes at least one window, whereby a child depositing one of said coins may observe the release of an additional coin into said bank.
